UNITED STATES PATENT OFFICE

2,257,396

TOP STRUCTURE FOR COOKSTOVES

Claude E. Parker, Chicago, Ill., assignor to Gas Products Corporation, Chicago, Ill., a corporation of Illinois

Application May 11, 1939, Serial No. 272,984

18 Claims. (Cl. 126—39)

The invention pertains to gas cookstoves and has particular reference to a new and improved cooking top for such stoves.

The primary object of the invention is the production of a new and improved cooking top for gas cookstoves, which partakes of the characteristics of both the open and closed types in that it effectually conceals the burners, mixing tubes and other unsightly parts as in the case of tops of the closed type, and at the same time provides for the effectual application of the heat of the burners directly to cooking utensils supported upon the top, as in tops of the open type.

A further object of the invention is to provide in combination with a main cooking top panel having a plurality of openings therein, auxiliary top units substantially closing the openings in the top panel so as to cooperate therewith in the formation of a substantially closed top wall, and fashioned to provide vertically shallow chambers beneath the cooking utensils adapted to receive and confine the flames of the underlying burners close to the utensil bottoms so as to utilize to the utmost advantage the heat of the burners.

Another object is to provide a new and improved cooking top which is especially constructed to minimize loss of heat by conduction or radiation whereby to intensify the application of the heat of the burners to the cooking utensils.

Still another object is to provide a combination burner cover and heat intensifying unit which harmonizes in appearance with the top panel, which is capable of withstanding without deterioration the intense heat of the burner flames, and which causes any food deposits on the top face of the unit to be burned so completely as to permit easy removal and maintenance of the top in a sanitary and attractive condition.

A further object is to provide an improved burner and a heat intensifying cover unit therefor adapted to effect a more uniform distribution of heat to the entire area of the bottom of a cooking utensil.

Another object of the invention is to provide a burner structure embodying a novel arrangement for supplying secondary air to both the inner and outer sides of flames issuing from generally peripherally disposed ports in the burner head and of such character as to retain relatively constant conditions of combustion, irrespective of the presence or absence of a utensil above the structure.

Still another object is to provide a burner structure embodying an open center burner head and an overlying superstructure including utensil

supporting fingers located intermediate spaced groups of fuel emission apertures in the burner periphery so as to be out of the direct path of flames from the latter, and so correlated with the burner as to direct and control an updraft of secondary air rising through the open center of the burner, and feed it to flames, the flow of such air beneath the fingers also serving to cool and thereby protect the same.

The objects of the invention above set forth, together with other and ancillary advantages are attained by the construction and arrangement shown by way of illustration in the accompanying drawings forming part hereof, in which:

Fig. 1 is a fragmentary plan view showing one end portion of a top structure embodying the invention.

Fig. 2 is a similar view showing one of the burner openings with the auxiliary top unit removed and exposing the underlying burner.

Fig. 3 is a fragmentary longitudinal section taken substantially in the plane of line 3—3 of Fig. 1, the section being taken on a larger scale.

Fig. 4 is a fragmentary plan view showing one of the auxiliary top units on a larger scale than shown in Fig. 1, such unit being in position in an opening in the top panel.

Fig. 5 is a fragmentary vertical sectional view taken approximately in the plane of line 5—5 of Fig. 4 and illustrating the manner of supporting the burner and auxiliary top unit.

Fig. 6 is a fragmentary edge elevational view of the structure shown in Fig. 5 but showing a supporting lug on the top panel in section.

Fig. 7 is a fragmentary plan view of one of the mixing tubes and illustrating the construction of the inner end portion thereof.

Fig. 8 is a view in edge elevation of one of the auxiliary top units and the burner supported in position in the main top panel, the latter being shown in section.

Fig. 9 is a transverse sectional view through the auxiliary top unit and burner taken approximately in the plane of line 9—9 of Fig. 4 and showing the formation of a chamber between the top unit and the bottom of a utensil within which the burner flames are confined.

Fig. 10 is a perspective view of metallic carrier for the ceramic elements composing the auxiliary top unit.

Fig. 11 is a perspective view of one of the burners.

Figs. 12 and 13 are perspective views showing respectively two forms of ceramic elements comprising the auxiliary top unit.

The improved cooking top comprises, in general, a main top panel 10 having a plurality of openings 11 therein disposed above burners 12, and auxiliary top units 13 substantially filling the openings 11 but providing for the passage therethrough of the burner flames for direct application to the bottoms of the utensils. In the present instance one end of a cooking top is shown, having front and rear burners with auxiliary top units of a diameter corresponding to that of cooking utensils of good size. The preferred relative proportioning of the parts is indicated by the representation in Fig. 9 of a utensil *a* of a diameter of eight inches.

The burners 12 are of the Bunsen type, receiving a supply of mixed air and gas from a suitable source. Herein the burners have supply pipes or mixing tubes 14 and 14' each permanently connected at its inner end to the bottom of a hollow burner head and provided at its outer end with an air mixing housing 15 equipped with adjustable valves or shutters 16 and receiving a supply of fuel gas under valve control in any suitable or preferred way. In the present instance each burner head is generally triangular in form (Figs. 2 and 11). Thus it is shaped to provide three arms 17 with a central portion having three air openings 18. The arms provide three arcuate outwardly facing sides drilled to provide the principal outlet for the gaseous mixture, comprising three horizontal rows of fuel discharge ports 19.

The auxiliary top units 13 are especially constructed for the performance of two important functions, of which the first is to provide individual covers cooperating with the main top panel 10 in the formation of a substantially closed cooking top, and the second to intensify the application of the heat of the burners to the cooking utensils. Accordingly, an important feature in the construction of each auxiliary top unit is the provision of a wall structure apertured for the passage of the burner flames and having a smooth and durable top facing which harmonizes in appearance with the top panel, is substantially impervious to the absorption of liquids, and is capable of resisting effectively stains and discoloration. The apertured wall structure constitutes in effect a hearth between which and the bottom of an overlying utensil is defined a vertically shallow combustion chamber serving to confine the burner flames for the effectual application of the heat thereof to the utensil. Accordingly, it is of vital consequence that the top facing be adapted to withstand without deterioration the intense heat of the flames thus confined between such top facing and the bottom of the utensil. Another important feature is the provision beneath the top facing of a layer of heat-insulating material serving to reduce to a minimum the loss of heat by dissipation to the associated parts of the stove structure and to the surrounding atmosphere. Finally each unit is constructed to provide a multiplicity of radiating elements adapted to be heated by the burner flames to a state of incandescence and serving to promote complete combustion as well as to augment the application of heat to an overlying utensil.

In the provision of a wall or hearth having a top facing with an underlying layer of insulating material for the purposes above set forth, a ceramic structure comprising a base or body of relatively porous refractory material and a top fac-

ing of vitreous material has been found to be particularly effective. Accordingly in the preferred embodiment of the invention each auxiliary top unit comprises a ceramic hearth-like structure supported substantially in the plane of the top panel 10 and cooperating with an overlying cooking utensil to define a vertically shallow combustion chamber *c*. For convenience in manufacturing the ceramic structure or hearth is composed of a plurality of separate sections coating to provide a peripheral shell 13^a and a central cap 13^b, the various elements being mounted upon a metallic carrier so as to constitute a unitary assembly adapted for easy removal from the main top panel when desired as for purposes of cleaning.

The units 13 are preferably circular in form and are suitably supported in the openings 11 of corresponding shape in the main top panel. To provide a multiplicity of heat radiating elements the peripheral shell 13^a is formed with an upper fluted surface forming in this instance radial ribs 13^c projecting upwardly from the top face of the shell and arranged so as to be lapped by the undersides of the flames issuing from the burner so as to be rendered incandescent, as hereinafter more fully described. As shown in Fig. 9, the inner end portions of the ribs 13^c are made extremely low and only the outer end portions are of sufficient height to project into the flames.

As best seen in Figs. 3 and 4, each of the units 13 is composed of six sections in the form of separate ceramic elements including three similar peripheral segments 20 of generally elliptical form and three relatively narrow radial arms 21. The latter are respectively interposed between the segments 20 and their outer end portions contact with the segments to form a continuous perimetric zone constituting the outer peripheral shell 13^a. The inner end portions of the arms cooperate to form the central spider-like cap 13^b overlying the burner.

The ceramic elements are especially constructed so as to be capable of withstanding heat and impact shocks. To this end each element comprises a body or base 22 of tough relatively porous refractory material of low heat conductivity, and a thin coating or top facing 22^a of vitreous material fused onto the base at a high temperature as, for example, 2600° F. The base material lends strength and durability to the structure, and the vitreous coating provides a glazed surface which is impervious to liquid and will not stain or become discolored in use. Moreover it is highly resistant to wear or abrasion, is capable of being cleaned easily, and constitutes an effective heat reflecting surface.

The metallic carrier for supporting the ceramic elements 20 and 21 in assembled relation comprises in the present embodiment (see Fig. 10) a thin narrow peripheral ring 23 having inwardly projecting portions 24 apertured as at 25 for lightness in construction and coating with the ring to support the peripheral segments 20. Midway between the apertured portions 24 are narrow radial fingers 26 (Fig. 3) underlying and supporting the radial ceramic arms 21.

The means for supporting the utensils are preferably made as a part of the auxiliary top unit 13, although it will be understood that if desired, separate utensil supports may be provided in accordance with well known practice. As herein shown, the utensil supports are composed in part of ribs 27 formed integral with the radial ceramic arms 21 at the inner ends thereof, and in part

by metallic arms 28 cast integral with the carrier ring and providing extensions of the ribs 27. The location of the utensil supports 28 above the ceramic arms 21 is advantageous in that the supports are not impinged upon by the burner flames and interpose no obstruction in the paths of the flames as in conventional stoves.

Each of the utensil-supporting arms 28 (Figs. 3, 4 and 10) is formed on the upper end of an upright standard 29 and one end thereof overlies the outer portion of one of the radial ceramic arms 21 so as to form a continuation of the rib 27. The other end of the arm 28 projects radially outward in overlying relation to the top panel 18 but out of contact therewith.

The fingers 26 are formed separately from the carrier ring 23 and when fastened in place by means of screws 30 (Fig. 3) coat with the ring and the arms 28 thereon to hold all of the ceramic elements in position on the carrier. As shown in Fig. 9, the ceramic arms 21 are grooved on their undersides to receive upwardly offset inner end portions of the fingers 26, the outer ends of the fingers being received in recesses 31 formed in the underside of the ring 23. The ceramic arms are held against outward movement by the standards 29 and against inward movement by the offset shoulder portions of the fingers.

In order that the segmental or peripheral elements 20 may also be secured in position by the fingers 26, the ends of these elements 20 are rabbeted as at 31^a (Fig. 8) for interlocking engagement with the opposite sides of the radial arms 21. Also the carrier ring 23 is provided with a peripheral flange 34 engaging in grooves 35 in the outer peripheral edge portions of the segments 20 to retain the latter against radial movement in an outward direction. Movement in the opposite or inward direction is prevented by abutment with the sides of the arms 21 at the outer ends of the latter.

It will be seen that the metallic carrier for the ceramic structure wholly underlies the same so that no metal parts of the unit 13, except for the supports 28, are exposed. To receive the standards 29 the ends of the ceramic arms 21 are suitably notched.

As above set forth the auxiliary top units 13 are apertured for the passage of the flames of the underlying burners. Preferably the openings provided for this purpose are so correlated with the burner proper that the latter is substantially concealed from view, with the burner outlet ports 19 disposed in underlying relation to the ceramic arms 21 so that the latter guard the ports against the entry of spilt-over liquids. Also the burner ports are so arranged relative to the opening in the structure that the flames issuing from the burner project laterally outward in close proximity to the peripheral shell of the cover. Preferably the discharge ends of the ports 19 are disposed in a horizontal plane above the inner edges of the segments 20 (see Fig. 9) so that flames issuing from the ports project outwardly above the top faces of the segments.

In the present embodiment each auxiliary top unit 13 has three generally arcuate slots 38 (Fig. 4), each defined by the inner edge of one of the ceramic segments 20 and by the lower side edges of two of the radial ceramic arms 21. As best seen in Fig. 9, the top faces of the segments 20 slope gently downward and inward toward the burner, and the radial arms are positioned horizontally with their top faces substantially in the plane of the outer edge portions of the segments,

5 with the side faces of the arms well above the inner edges of the segments. By this arrangement the radial arms, together with the utensil supports 27, 28, constitute division members dividing the combustion chamber c into three generally elliptical spaces having inlet openings at their inner edges formed by the slots 38 and outlet passages 39 defined by the outer portions of the segments and by the bottom of an overlying utensil. The outlet passages are preferably restricted at their outer ends by arcuate rims 40 shaped to deflect the discharging gases upwardly toward the utensil bottom. Also it will be seen from Figs. 4 and 9 that the outlet passages 39 are 10 relatively longer and narrower than the inlet openings formed by the flame slots 38.

15 In addition to the openings provided by the slots 38, each of the auxiliary top units has a central opening 41 defined by the inner ends of the radial arms 21. Through this opening flames project from three radial rows of port holes 42 centrally of the burner, or from a central simmering burner (not shown) which may be provided if desired. The ends of the radial arms 20 are spaced a short distance apart to form radial 20 passages 43 establishing communication between the central opening 41 and the arcuate flame slot 38, the burner being provided with radial gas discharge slots 44 positioned centrally of the passages 43 for the purpose of conducting a lighting 25 flame between the outer and inner outlet ports 19 and 42.

30 In the present instance both the auxiliary top units and the burners 12 are independently supported by the main top panel 10 through the medium of a plurality of lugs projecting inwardly from a flange 46 depending from the top panel. The ends of the burner arms are reduced in width to form tongues 47 resting upon a pair of 35 circumferentially spaced lugs 45; and to insure proper positioning of the burner, the lugs 45 are notched to receive the outer ends of ribs 48 40 formed on the undersides of the burner arms. A portion of the burner head weight is also carried by the manifold at the front of the stove 45 (Fig. 1) and to which the burner heads are connected by suitable supply conduits as heretofore described.

45 The auxiliary top unit also rests upon the lugs 45 and additionally upon an intermediate lug 45^a. The lugs 45 are made of a width adjacent the flange 46 somewhat greater than the tongues 47 so as to be engaged by the bottom of the carrier ring 23 at opposite sides of the recesses 31, the latter being of a depth adapted to receive the tongues 47. If desired, the inner ends of the radial ceramic arms 21 may be supported by engagement of the fingers 26 with upstanding lugs 48^a cut integral with the burner.

50 In addition to the lugs 45 and 45^a a plurality of lugs 48 are provided on the flange 46. Normally these lugs 48 are not engaged by the carrier ring but merely underlie the same with a slight clearance between them so as to be engaged only in the event of unusual pressure or 55 weight on the auxiliary top unit at one side of its center. The unit-supporting lug 45^a positioned midway between the notched lugs 45 (Fig. 2) terminates short of the corresponding burner arm to facilitate the assembly of the parts.

60 Referring now to Figs. 2, 3 and 7 the construction of the burner 12 in its connection with the supply pipe 14 will be understood. The burner is preferably designed to effect a uniform distribution of the heat of the burner to the cooking

utensil. As already indicated it is of generally triangular form having three radial arms 17 providing three external sides in which are drilled the three rows of ports 19. By making the sides arcuate in form, the central ones of each row of ports 19 are positioned closer to the center of the burner. As shown each row of ports 19 extends throughout the entire length of an arcuate side of the burner to form a large burner, for example, 12,000 B.t.u. capacity. In the case of burners of lower rated capacity, say 9,000 B.t.u.'s, a few of the ports at each end of the row may be omitted. Thus the burners are of identical construction in either case excepting only that the number of port holes is varied.

Each hollow burner arm 17 communicates at its inner end with one of three chambers 50 respectively registering at their undersides with three intercommunicating chambers 51 formed in the head 52 at the inner end of the mixing tube 14 or 14', the two heads being secured together by means of screws 53. Between the chambers 50 of the burner, the central air openings 18 are formed, which openings communicate at their lower ends with a central star-shaped opening 54 in the head 52 of the mixing tube. Through the central air passage thus formed, secondary air is supplied to the three radial rows of port holes 42. The latter are drilled in radial extensions 55 from each of the chambers 50 of the burner head, the port holes being in each instance inclined upwardly and inwardly so as to direct flames upwardly toward the center of a utensil supported above the burner.

In addition to providing for the passage of the burner flames, the arcuate slots 38 constitute an inlet for secondary air to the combustion chamber c. Thus it will be seen that air is permitted to pass upwardly around the burner providing an ample supply of oxygen for the combustion of the gases issuing from the ports 19 and supplying particularly the undersides of the flames. The secondary air supply for the central ports 42 is received through the passages formed by the openings 18 and 54 centrally of the burner structure. Moreover the arrangement is such that such central supply of secondary air may pass radially outward along the upper sides of the burner arms so as to feed oxygen to the upper sides of the flames issuing from the ports 19. In this connection it will be observed that each of the ceramic arms is spaced above the corresponding burner arm, thus permitting the flow of air radially outward above the port holes 19.

As shown in Fig. 9, the port holes 19, constituting the principal gas discharge outlet for the burner, are drilled generally horizontally but are inclined upwardly at a small angle, that herein shown being approximately 30 degrees from the horizontal. Also the ports are disposed substantially in the plane of or slightly above the inner edges of the ceramic segments 20. Thus flames issuing from the burner project outwardly and somewhat upwardly immediately above the face of the ceramic elements 20 which also slope upwardly and at an angle substantially corresponding to that of the flames. Due to the generally horizontal projection of the flames, the burner ports may be positioned closer to the bottom of the utensil as determined by the plane of the utensil seating surfaces, and throughout the major part of their length the flames are closely confined between the opposed surfaces forming the combustion chamber. Thus the hottest portions of the flames, namely, the tip portions of

the outer cones are effectively utilized. Due to the sloping top faces of the segmental elements 20, the central portion of the combustion chamber c is relatively deep (for example one inch). Accordingly, ample space is provided for the initial expansion of the gases, thus promoting complete combustion. Moreover, these sloping surfaces tend to reflect the heat of the flames upwardly and somewhat inwardly toward the center of the utensil and above the ceramic arms 21.

Contributing to the distribution of the heat of the burner uniformly to the cooking utensil as well as to the intensity of its application is the radiant character of the auxiliary top unit obtained by the provision of the radiating elements disposed closely adjacent the high temperature zone immediately beneath the utensil bottom. As hereinbefore indicated these elements take the form of radial ribs 13^c which are closely spaced and project upwardly from the top faces of the segmental elements 20 a distance such that their upper edges are disposed directly in the path of the tip portions of the flames issuing from the burner but out of the paths of the central oxidizing cones of the flames. In addition the inner ends of the ceramic arms are shaped to provide radiating elements adapted to be heated by the flames issuing from the center port holes 42 and the radial slots 44; and the side faces of the arms 21 may be fluted as shown at 22^a in Fig. 4.

It will be observed that since the ribs project upwardly into the flames, the lower sides thereof are more effectively utilized. Thus the lower portions of the ribs define between them channels for the passage of gases of a somewhat lower temperature than the flames, possibly including a film of secondary air for the undersides of the flames, whereas the upper portions of the ribs are disposed in direct contact with the hottest parts of the flames. As a result, in the operation of the burner, the upper edge of these radiating ribs 53 becomes incandescent, promoting combustion of the gases and transmitting the heat of the undersides of the flames to the utensil by radiation.

As is well known the base portions of the flames are relatively cool, and it will be observed that by the construction provided, only such base portions are unconfined at their lower sides. In this connection, it is to be observed that due to the substantial length of the slots 38 they may be made relatively narrow, with the inner edge of the segments 20 closely spaced from the sides of the burner. Thus it is that the intense heat of the burner flames is confined in the combustion chamber immediately adjacent the point of application of heat to the utensil, and instead of being reflected downwardly by the utensil into the burner box, it is reflected by the ceramic elements 20 upwardly and somewhat inwardly due to the sloping surfaces of the elements. The central area of the utensil is, of course, heated directly by the flames issuing from the central port holes 42 and radial slots 44, or by the simmering burner if such be employed.

To provide for the passage of cool air between each of the auxiliary top units and the top panel, they are made of a diameter somewhat less than the openings 11. Thus an annular slot 56 (Figs. 4 and 8) is formed between the depending flange 46 of the top panel and the outer vertical edge of the unit. This provision for the passage of cool air has been found to be of substantial importance in connection with the relatively low

heat conductivity of the ceramic elements. Thus even though the top surface of the cover structure is heated to an extremely high temperature the outer vertical side edge of the cover structure is maintained relatively cool so that any food spillage may be easily removed.

It will be observed that the auxiliary top units 13 cooperate with the main top panel 10 to provide in effect a closed cooking top having a plurality of circular depressions or recesses for the reception and close confinement of the flames projected outwardly beneath the utensil bottoms; and with the top units composed of ceramic material as in the present preferred embodiment of the invention, with top faces of a smooth hard, vitric material, and a relative porous base of low heat conductivity, the heat of the burner is utilized to the fullest possible extent through reflection and radiation to the utensil. In this connection it will be observed that with the flames projecting outwardly into the vertically shallow combustion spaces, the upper sides of the flames lap the utensil bottom while the undersides thereof follow closely the top faces of the segmental elements 20. Although the top faces of the elements are heated to a high temperature, this heat is effectually utilized by reflection with a minimum of loss by conduction.

In addition to the improved heat reflecting character of the elements obtained by the use of a hard vitric coating, the latter performs other important functions contributing substantially to the production of a commercially successful top structure. Thus the ability to maintain an attractive appearance is assured due to the fact that the hard vitric coating is substantially impervious to the absorption of liquids, effectually resists stains, and is capable of easy cleaning. In this latter connection it has been found that the intense heat to which the top faces of the ceramic elements are subjected in the operation of the burner is an important factor in keeping the structure clean. In fact extensive tests have shown that any food products deposited on the smooth hard top facing of the cover, as a result of spillage or boiling over of the contents of a utensil, are so thoroughly burned or consumed that upon cooling, it is possible to remove the residue or ash from the elements merely by a slight blast of air or by means of a damp cloth. On the other hand, because of the low heat conductivity of the ceramic structure, coupled with the cooling effect of the air current passing upward around the cover, the outer peripheral side wall of the cover is maintained at a sufficiently low temperature that any food products deposited thereon will not bake on and can be readily removed.

Finally the construction and arrangement provided operates to limit the supply of secondary air substantially to that required for complete combustion and to prevent the inflow of air inwardly beneath the utensil, thereby minimizing loss in efficiency due to the admission of an excessive amount of cool air. This result is accomplished by restricting the outlet passages 39 formed between the utensil bottom and the peripheral shell. Also the ribs 53 projecting upwardly into the vertically shallow combustion chamber and into the outer passages 39 serve to retard the escape of the gases of combustion outwardly. Since these ribs project radially inward from the outer edge of the cover structure they coact with utensils of varying sizes in providing a restricted outlet passage.

Secondary air is thus supplied to the combustion chamber solely through the flame slots 38 and the central openings 41 communicating with the central openings 18 of the burner. Moreover such a restricted outlet passage has the effect of retarding the escape of the gases so that the latter are confined in the combustion chamber beneath the utensil for a longer period of time.

This application is a continuation-in-part of my co-pending application Serial No. 235,961, filed October 20, 1938.

The present application was also copending with my still earlier-filed, and now abandoned, application, Serial No. 84,880, filed June 12, 1936, and which earlier-filed application showed a specifically different form of cookingstove top structure having certain features in common with that here disclosed and as to which certain claims herein are generic.

It should be understood that a number of features of the cooking top and its elements disclosed but not claimed herein are described and claimed in various other of my copending applications for patent. In particular, the burner head per se, and which is of general utility irrespective of its use with or without a cover structure, is described and claimed in my copending application Serial No. 324,470, filed March 18, 1940, and which is a continuation in part of this present application. The hearth or closure structure herein shown also constitutes per se a sub-combination of the complete cooking top herein shown and is so described and claimed in my copending application Serial No. 326,883, filed March 30, 1940, and which is a continuation in part of this present application. The air wash system for cooling the top panel and the top structure supporting arrangement herein disclosed, as well as certain improvements thereon, are described and claimed in my copending application Serial No. 324,293, filed March 16, 1940, and which is a continuation in part of this application. A three-arm utensil-seating structure of specifically different form from that herein shown, but of the same general character, is disclosed and claimed sufficiently broadly to include the present structure in my copending application Serial No. 321,498, filed February 29, 1940, and which is a continuation in part of this present application. The feature herein shown, of locating the intake adjustment mechanism for one or both of a pair of front and rear burners for access through one of the burner holes in the top panel, is also embodied in the specifically different top structure disclosed in my copending application Serial No. 321,499, filed February 29, 1940, and is claimed therein, such application being a continuation in part of the present application.

I claim as my invention:

1. A cooking top structure for gas cookstoves comprising, in combination, a burner having a plurality of equidistantly spaced radial arms shaped to form a plurality of outwardly facing arcuate sides, and a cover structure for the burner having a plurality of radial portions respectively overlying said burner arms and intervening portions sloping gradually downward and inward toward the burner between said radial portions and coacting therewith to form a plurality of arcuate slots, said burner having fuel discharge means in said arcuate sides arranged to project flames outwardly above said intervening portions of the cover structure.

2. A cooking top structure for gas cookstoves

comprising, in combination, a burner having three equidistantly spaced radial arms shaped to form three outwardly facing arcuate sides, and a cover structure for the burner having three radial portions respectively overlying said burner arms and intervening portions sloping gradually downward toward the burner between said radial portions and coacting therewith to form a plurality of arcuate slots, said burner having fuel discharge means in said arcuate sides arranged to project flames outwardly above said intervening portions of the cover structure, and utensil supports carried by said cover structure and respectively disposed above said radial portions thereof.

3. In a gas cookstove, the combination of a 15 star-shaped burner and a cover structure comprising a central spider having arms overlying the burner and outer portions providing wide upwardly facing heat reflecting surfaces sloping gradually downward and inward toward the 20 burner between said arms, the inner edge of said outer portions coacting with the side edges of said arms to define a plurality of slots, and said burner having a fuel discharge outlet adapted to project flames outwardly through said slots and 25 above said sloping surfaces.

4. In a gas cookstove the combination of a burner having a plurality of equidistantly spaced radial arms, and a combined heat intensifier and cover comprising a plurality of arms directly overlying the burner arms but spaced therefrom, and a peripheral shell externally of the burner and having inner edge portions spaced downwardly from the side edges of the cover arms to 30 form elongated slots, said burner having fuel discharge means for projecting flames outwardly through said slots and having a central air passage for supplying secondary air to the spaces between the upper sides of said burner arms and the lower sides of the cover arms.

5. In a gas cookstove the combination of a burner having a central opening therethrough for the passage of secondary air and a plurality of equidistantly spaced radial arms, and a combined heat intensifier and cover comprising a plurality of arms directly overlying the burner arms, a utensil supporting element disposed centrally above each of said cover arms, and a peripheral upwardly facing shell extending outwardly from the burner and spaced from the cover arms to 35 form elongated slots, said burner having fuel discharge means for projecting flames outwardly through said slots and said cover arms coacting with the burner arms to provide horizontal passages communicating with the central opening in the burner for supplying air to the upper sides of said flames, the flow of air through said passages beneath said cover arms also serving to cool such arms and the utensil seating elements above the same.

6. In a gas cookstove the combination of a burner having equidistantly spaced radial arms, and a cover structure comprising a plurality of radial arms overlying the burner arms with the inner ends of said cover arms cooperating to form a central opening and to define passages extending radially outward from said opening above said burner arms, said burner having a central opening, a plurality of fuel discharge ports projecting inwardly and upwardly into the opening formed between the cover arms, a plurality of outer fuel discharge ports projecting outwardly from the burner arms, and radial fuel discharge slots positioned to project flames upwardly into 40

said radial passages and serving to connect the inner and outer fuel discharge ports for lighting purposes.

7. In a gas cookstove the combination of a 5 burner having a plurality of equidistantly spaced radial arms, and a cover structure for the burner comprising radial portions overlying the burner arms, said burner arms having fuel discharge means for projecting flames laterally outward from beneath the cover arms, and radial utensil supporting members respectively disposed centrally above said radial cover arms.

8. In a gas cookstove, the combination of a main top panel having an opening therein, a top burner comprising a burner head, and a combined heat intensifier and cover for the burner head of refractory material and comprising a cap directly overlying the burner head and a peripheral shell surrounding the burner in spaced relation thereto, and means for supporting a cooking utensil spaced a short distance above said cap, said shell having a top and outer side facing of vitric material with the top facing terminating at its periphery adjacent the edge of the opening in the top panel and coacting with the bottom of a utensil resting on said supporting means to define a combustion chamber having an outlet at the periphery of the shell opening outwardly beneath the utensil and in a plane above said top panel, said burner having fuel discharge means for projecting flames outwardly into said combustion chamber with the tip portions of the flames confined between said vitric top facing of the shell and the bottom of the utensil.

9. A cooking top for gas cookstoves comprising, in combination, a main top panel having an opening therein, a burner disposed centrally below said opening and the perimeter of said opening being spaced laterally from such centrally disposed burner, said burner having fuel discharge means for projecting flames laterally outward toward the perimeter of said opening and upwardly above the plane of said top panel, a combined heat intensifier and cover for the burner removably supported in said opening independently of said burner and substantially in the plane of the panel, said cover being apertured for the passage therethrough of flames issuing from the underlying burner and serving substantially to conceal the burner beneath it, and means for supporting a utensil with its bottom in closely spaced relation above the face of said cover, said cover being adapted to coact with the bottom of a cooking utensil on said supporting means to define a vertically shallow chamber for the reception and close confinement of the flames of the burner.

10. In a gas cookstove, the combination of a burner having a plurality of radial arms, a plurality of utensil supports disposed above respective ones of said burner arms and extending longitudinally along them, said burner arms having fuel discharge means for projecting flames laterally away from the utensil supports overlying the burner arms from which the flames issue, and a refractory cover overlying and generally concealing the burner, said cover being apertured for the issuance of the flames in position to play upon the bottom of a utensil on said supports and comprising arm portions interposed in thermal insulating relation between the burner arms and the respective overlying utensil supports.

11. In a gas cookstove, the combination of a 70 burner, a generally horizontal cover overlying

and substantially concealing said burner, utensil supports projecting radially inward from the periphery of the cover toward its center and presenting seating surfaces to support a utensil bottom in closely spaced relation above said cover, said cover being apertured for the passage of flames from the burner into the space between the utensil and cover, and said burner having fuel emission means for projecting flames through the cover aperture beneath the utensil bottom but in a direction generally laterally away from the utensil supports to prevent direct flame impingement on the latter.

12. In a cooking top for a gaseous fuel cooking stove, the combination of a burner head having a generally central opening therethrough for an updraft of secondary air and having fuel emission apertures therein located in segregated zones spaced peripherally about the head, a superstructure including utensil supporting finger portions projecting radially of the head and lying above the portions of the latter intermediate said zones of fuel emission apertures to be out of the direct path of flames issuing from the latter, and said superstructure presenting a bottom face closely spaced from and coacting with the burner head to define air passages leading outward from the secondary air supply opening in the head to said fuel emission apertures, the flow of air through said passages serving also to cool said overlying superstructure.

13. In a cooking top for a gaseous fuel cooking stove, the combination of a burner head having a generally central opening therethrough for an updraft of secondary air, a plurality of fingers projecting radially inward above the head toward the central axis of the latter, said head having a plurality of fuel emission apertures therein disposed in zones spaced peripherally about the head and intermediate said fingers so that flames issuing from the same will not impinge directly on said fingers, said fingers presenting utensil seating ridges on their tops extending generally longitudinally of the same, the inner end portions of said fingers being splayed laterally to overlie the head, and the adjacent surfaces of the head and fingers defining therebetween air passages extending from the central opening in the head to the fuel emission apertures for the flow of secondary air through said passages to flames issuing from said apertures and for the cooling of said fingers beneath which such flow of air passes.

14. In a gas cookstove, the combination of a top panel having an opening therein, a burner below and centrally of said opening with fuel discharge means in its upper portion, and a combined cover and utensil supporting unit removably supported in said opening in the top panel substantially in the plane thereof and comprising a central section overlying the burner so as to substantially conceal the same and providing utensil seating surfaces disposed in a plane above the top panel, an outer section depressed relative to the central section and providing wide upwardly facing heat reflecting surfaces extending from said central section outwardly toward the periphery of the opening in the top panel, and outlet means disposed between the top faces of the central and outer sections at the outer and inner edges thereof respectively for the escape of products of combustion outwardly between said outer section and the bottom of a utensil resting on said seating surfaces.

15. A gas cookstove having, in combination, means for supporting a cooking utensil with its bottom surface exposed, a burner having a plurality of radial arms with outlet means at opposite sides thereof for discharging gaseous fuel upwardly and laterally, said fuel discharge means being positioned to cause the flames or gases while in process of combustion to play directly upon the bottom surface of a utensil resting on said means, and a hearth located immediately beneath said utensil supporting means to define between the top surface of the hearth and the utensil bottom surface supported on said means a vertically shallow combustion space, said hearth comprising a generally horizontal wall overlying and substantially concealing the burner and having slots positioned at opposite sides of the burner arms for the passage of such flames into the combustion space, and said slots being only partially underlaid by the burner arms to permit an updraft of secondary air through the unclosed lower end portions of the slots to flames issuing from said burner outlet means.

16. A gas cookstove having, in combination, a burner having a plurality of radial arms with outlet means at opposite sides thereof for discharging gaseous fuel upwardly and laterally beneath a cooking utensil supported above the burner, and a hearth positioned above the burner to define a combustion space between the top surface of the hearth and the utensil bottom surface, said hearth comprising a refractory disk overlying and substantially concealing the burner and having slots disposed above and at opposite sides of the burner arms for the passage of burning gases into the combustion space, said disk having a plurality of utensil supporting ribs formed integral therewith and disposed between said slots, and said slots being only partially underlaid by the burner arms to permit an updraft of secondary air through the unclosed lower end portions of the slots to flames issuing from said burner outlet means.

17. A gas cookstove having, in combination, means for supporting a cooking utensil with its bottom surface exposed, a burner having a plurality of radial arms with outlet means at opposite sides thereof for discharging gaseous fuel upwardly and laterally beneath a utensil so supported, and a hearth located immediately beneath said utensil-supporting means to define a combustion space between the top surface of the hearth and the utensil bottom surface supported on said means, said hearth comprising a substantially flat refractory disk overlying and substantially concealing the burner, and a metallic carrier supporting said disk, said disk having a plurality of radial slots disposed at opposite sides of the burner arms for the passage of burning gases into the combustion space and said utensil-supporting means comprising a plurality of circumferentially spaced ribs rigid with said carrier and a plurality of ribs formed integral with the disk between said slots and disposed in substantially radial alignment with the ribs on the carrier.

18. A gaseous fuel cookstove comprising, in combination, a heat radiating burner top structure presenting a top surface, a gaseous fuel burner head located below said top structure and including a central section of ports distributed over only a small area in a horizontal plane and a second section of ports disposed laterally of said central section and directed laterally as

well as upwardly, means for supporting utensils having bottoms of widely different areas in closely spaced relation above said top structure, said top structure having a generally centrally located aperture therein for directing hot gases from said central port section substantially directly upward to the bottom of even a small utensil, and said top structure also having apertures therein located somewhat laterally of said second port section and bounded by a substan-

5 tially imperforate marginal portion of said top structure presenting a top surface of substantial lateral width so that hot gases from said second section of ports are spread laterally beneath the bottom of even a large utensil while being confined in effective heat exchange relation with the utensil in the space between said marginal portion of said top structure and the utensil bottom.
